MARTIN C. BERSTED, OF SAN DIEGO, CALIFORNIA

ELECTRIC FLATIRON

Application filed February 16, 1928. Serial No. 619,386.

My invention relates to heat-regulating electric heating apparatus, more particularly to electric flat irons, and the primary object of this invention is improvements over my 5 previous application for Letters Patent for electric flat irons, filed in the United States Patent Office September 28, 1922, Serial Number 591,094, and the objects of my improvement are: First, to provide a flat iron 10 of this class which is so constructed and in which the main portions are so supported relatively to each other at a main portion, that the various parts are permitted to expand freely, relatively to each other when heated; second, to provide an electric flat iron of this class which may be easily and 15 quickly assembled and disassembled, and in which the separately operative units are supported separately and may be easily replaced; third, to provide a contact making and breaking means for electric heating apparatus, operative by the distortions of a loosely mounted, expansible, thermostatic plate, when subjected to various heats; fourth, to provide a 20 contact making and breaking means for electric heating apparatus in which the operating expansible member is insulated from the contact making portions, or the electrically charged portions of the means, and in which 25 the movement of the contact making members is increased over the movement of the expansible members; fifth, to provide a contact making and breaking means of this class in which the contact making members are 30 rigidly supported and pivotally movable relatively to each other, and at all times retained in alignment with each other; sixth, to provide a mechanically operated thermo-indicator for electric heating apparatus; 35 seventh, to provide combined means for indicating the temperature of electric heating apparatus and manual means for adjusting the temperature of the apparatus at substantially the temperature desired; eighth, to 40 provide a novelly constructed, mechanically operated, thermo-indicating device; ninth, to provide as a whole a novelly constructed, heat-indicating, heat-adjusting and automatic heat-control means for electric heating apparatus; tenth, to provide as a whole a 45 novelly constructed, electric flat iron, and eleventh, to provide a flat iron of this class which is very simple and economical of construction proportionate to its functions, durable, efficient, compact, reliable, easily adjusted, easy to operate, and which will not readily deteriorate or get out of order. 55

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which: 60

Figure 1 is a plan view of my flat iron; Fig. 2 is a side elevational view thereof; Fig. 3 is a rear elevational view thereof, showing by dotted lines certain hidden portions thereof; Fig. 4 is a sectional elevational view thereof taken through 4—4 of Fig. 1, showing certain parts and portions in elevation to facilitate the illustration; Fig. 5 is an enlarged, sectional view of my iron taken through 5—5 of Fig. 4, showing certain parts and portions in elevation to facilitate the illustration and showing certain hidden and other parts by dotted lines; Fig. 6 is an enlarged, plan view of the contact making and breaking means of my flat iron, shown separate and apart therefrom; Fig. 7 is a transverse, sectional view of my flat iron taken through 7—7 of Fig. 4; Fig. 8 is a fragmentary, sectional, plan view taken through 8—8 of Fig. 4, showing in detail the mechanically operated, thermo-indicating device of my flat iron; Fig. 9 is a fragmentary, sectional view taken through 9—9 of Fig. 3 of the hook means connecting the casing members; and Fig. 10 is a fragmentary, sectional view of the flat iron taken through 10—10 of Fig. 4. 65

Like characters of reference refer to similar parts and portions throughout the several views of the drawings. 70

The base plate 1, insulating material 2, heating elements 3, upper plate 4, screws 5, main casing member 6, main screw 7, handle 100

supporting members 8 and 9, handle 10, handle bolt 11, name plate 12, thermostat support 13, terminal bolts 14, 15 and 16, insulating washers 17 and 18, washers 19, conductors 20 and 21, circuit breaking lever 22, spring 23, screw 24, breaker points 25 and 26, terminal posts 27, conductors 28 and 29, thermostat member 30, adjusting screw 31, screw adjusting lever 32, clamp screw 33, end 5 support and casing member 34, screw 35, thermo-indicator support 36, screw 37, thermo-plates 38 and 39, screw 40, indicating finger 41, pivot member 42, indicating point 43, mica plate 44, dial plate 45, and the terminal protector and support 46, constitute 10 the principal parts and portions of my automatic heat-regulating electric flat iron.

The lower and heating portion of my flat iron, consisting of the base plate 1, the insulating material 2, positioned thereon, the electric heating elements positioned between the insulating material, the upper plate 4 positioned above the insulating material and clamping the latter between the plates 1 and 25 4, which plates are screwed together by the screws 5, is of the conventional construction.

The main casing member 6, enclosing the members 2, 3 and 4, is secured to the upper plate 4 by the main screw 7, and is so constructed at its upper portion as to receive the lower ends of the handle supporting members 8 and 9, which extend respectively through slots 6^a and 6^b in the casing member 30 6 and are secured in position by the main screw 7. At the upper extended ends of said handle supporting members is secured the handle 10 by means of the bolt 11, which handle member is provided with finger grooves 10^a at its lower portion. The head of 40 the main bolt 7 is sunk into a recess in the casing member 6 and is concealed by a plate 12 which serves as a name plate and is secured to the member 6 by a lug 12^a at one end and a resilient catch portion 12^b at its 45 other end, extending into slots in said casing member.

The upper rear portion of the casing member 6 is enlarged and so constructed as to receive the thermostat operated switch 50 mechanism, which is preferably assembled in a separate complete unit supported on the thermostat support 13, which support is preferably secured at its one end only by the screw 7 to permit expansion and contraction 55 in all directions, said one end being positioned between the lower ends of the handle supporting members and the upper plate 4. It will be noted that the support 13 is provided with lugs 13^c near its free end which 60 rest in the notched portions 6^d at the rear end of the casing 6 and are adapted to support the free end of the support 13, permitting free expansion and contraction of said support. Said thermostat support 13 is provided with a pair of laterally extending lugs 65

13^a and 13^b, through which extend respectively the terminal bolts 14 and 15, which are insulated therefrom by the insulating washers 17 and 18, preferably of mica. The holes in the lugs through which the terminal bolts 70 extend are considerably larger than the diameter of the bolts and are positioned centrally therein by the insulating washers 17, which are positioned in recesses in said lugs. Positioned between the insulating washers 75 and the head and nut of the bolts are the washers 19, preferably of metal. Secured to said bolts, intermediate the metal washers and the heads thereof, are the conductors 20 and 21 which are secured at their opposite 80 ends respectively to the free ends of the electrical heating element 3, as shown best in Figure 5 of the drawings. Pivotaly mounted in and above the support 13 is the circuit 85 breaking lever 22 by means of the spaced lugs 22^a in the form of hooks at its one end, which extend into the support 13, as shown best in Figures 5 and 6 of the drawings. At the opposite end of the lever 22 is provided a guiding lug 22^b, which extends downwardly between the spaced guiding lugs 13^c 90 at the end of the lugs 13^a. It will be noted that the lugs 22^a at the one end of the lever 22 are adapted to keep the same from tilting, and the lug 22^b is adapted to prevent the lever from being shifted laterally. Near the end of the lever 22 provided with a guiding lug is a terminal bolt 16, extending therethrough and insulated therefrom as described, relative to the bolts 14 and 15. The 95 bolts 14 and 16 are also positioned in alignment with and adapted to engage each other and are provided at their engaging portions with breaker points 25 and 26 respectively, preferably of pure silver. The breaker 100 points of the bolts 14 and 16 are held in constant engagement with each other when the iron is not in use or when the heat is not sufficient to warrant their separation, by the 105 spring 23, secured to the support 13 by the screw 24, substantially as shown in Figures 110 5 and 6 of the drawings. The terminal bolts 15 and 16 are connected to the terminal bolts 27 by the conductors 28 and 29. The terminal bolts 27 are supported in and insulated from the upwardly and inwardly turned portion 13^d of the support 13 by insulating washers 17 and 18, and other washers 19, as described, relative to the terminal bolts. Provided at the rear portion of the supports 13 115 intermediate the lugs 13^a and 13^b is the circular recess 13^e in which is loosely positioned the thermostat member 30 in disc form. Said thermostat member 30 is composed of two plates of metal of different coefficients of expansion, secured together in any convenient manner, so that when heated the disc will be distorted upwardly at its central portion. It will be noted that it has been found by 120 experiment that the thermostat member 30 125

will operate more freely when loosely positioned in the support 13 as described. Mounted in the boss 22^c of the lever 22 and positioned centrally above the thermostat member 30 and adapted to engage the same is the multiple thread adjusting screw 31, which is accessible through the opening 6^c in the casing member 6. Mounted on said adjusting screw is the screw adjusting lever 32, frictionally secured thereto by the clamp screw 33, which lever extends through an opening 13^c and outwardly beyond the main casing member 6 and upwardly, from which end it is adapted to be shifted by the operator in various positions for obtaining various heats. It will be noted that the portion of the casing 6 contiguous to the lever portion extending above the casing is provided with the letters "L", "M" and "H", indicating respectively the positions of the lever for relative "low", "medium" and "high" temperature, as shown best in Figure 10 of the drawings. Secured to the rear portion of the main casing member 6 is the casing member 34, which serves as a partial support for the iron when positioned on its end and not in use, or a support for the thermo-indicating means, and for a guard for the lever 32. Said casing member is provided at its lower portion with lugs 34^a and 34^b which extend through openings in the main casing member, the lug 34^a being hook shaped, and is inserted first, and the other lug 34^b, being provided with an enlarged inner end, is adapted to be inserted into an enlarged opening in the main casing member and when forced downwardly into a reduced portion of the opening is adapted to retain the lug, and therefore the casing member 34, in position. Said casing member is retained in said position by the screw 35, extending into the thermostat support 13, as shown in Figure 4 of the drawings. Mounted in and secured to the casing member 34 is the thermo-indicator support 36 by the screw 37, which support extends through the opening 6^c of the casing member 6. Mounted near the inner end of said support is the pivot member 42 on which is mounted the indicating finger 41, which extends outwardly from said pivot member. The support 36 is provided at its opposite, outer end with an upwardly extending lug 36^a, to which are secured the thermo-plates 38 and 39 by the screw 40. Said thermo-plates each consist of two plates of metal of different coefficients of expansion, secured together in any convenient manner, and are positioned adjacent to each other and adapted to act simultaneously when subjected to the heat of the iron. Provided at the free end of the plate 38 is a lug 38^a provided with an elongated hole 38^b, which is adapted to receive a downwardly extending lug 41^a of the indicating finger 41, by which means the indicating finger is carried around its pivotal axis by the distortion of the thermo-plate when subjected to heat. The indicating finger 41 is provided near its pivotal support with laterally extending lugs 41^b and 41^c, which are adapted to engage the support 36 and limit the movement of the finger 41. Provided near the extreme end of said finger is a brightly colored indicator point 43, preferably a stone or other readily visible object. Directly above the circular path of the stone 43 of the indicating finger is a slot 34^c in the casing member 34, so that the movement of said finger may be easily seen. Covering this opening is the mica plate 44 which is secured in position by the dial plate 45 which is secured to the casing member 34 by lugs provided thereon and extending through holes in the casing member. The dial plate 45 is provided with notches and numerals to correspond with degrees Fahrenheit calibrated to correspond with the temperature within the casing member or of the flat iron. Surrounding the terminal posts 27 is the terminal protector and support 46, secured to the rear handle supporting member 9 in any convenient manner and resting at its lower end on the casing member 6. Said terminal protector is provided with a loop at its rear portion which, together with the outwardly extended portion of the casing member 34, serves as a support when the iron is hot and not in use.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

It is obvious from this construction that there is provided a flat iron in which the main portions are so constructed and supported relatively to each other that the various parts are permitted to expand freely when heated; that there is provided a flat iron in which the separately operable units are supported separately, and may be easily replaced, assembled or disassembled; that there is provided a contact making and breaking means for an electric heating apparatus, operative by the distortions of a loosely mounted, expansible, thermostatic plate, when subjected to various temperatures; that there is provided a contact making and breaking means in which the operating members are insulated from the contact making portions and in which the contact making members are guided by reason of each other and in which the movement is increased relatively to the expansible member; that there is provided a mechanically operated, heat-indicating, heating apparatus; that there is provided combined means

for indicating temperature and manual means for regulating the temperature of electrical heating apparatus at substantially the temperature desired; that there is provided 5 as a whole a novelly constructed, heat-indicating, heat-adjusting and automatic heat-control means for electric heating apparatus; and that there is provided a flat iron which is very simple and economical of construction proportionate to its functions, durable, 10 efficient, compact, reliable, easily adjustable, easy to operate, and which will not readily deteriorate or get out of order.

Having thus described my invention, what 15 I claim as new and desire to secure by Letters Patent, is:

1. In a heating apparatus, a contact making and breaking means, including a support, a single freely movable plate, capable of being 20 distorted by heat, loosely mounted on and encircled by said support, an arm secured at one end, positioned contiguous to said plate, a screw mounted in said arm, adapted to be engaged by said plate, a contact member 25 mounted in said support and another contact member mounted in said arm, adapted to engage said first mentioned contact member, and lever means secured to said adjusting screw for adjusting the latter.

30 2. In a heating apparatus, an electric contact making and breaking means, including a support, a single freely movable plate, capable of being distorted by heat, loosely mounted on and encircled by said support, an 35 arm secured at one end, positioned contiguous to said plate, a member mounted in said arm, adapted to be engaged by said plate, a contact member mounted in said support and another contact member mounted in said 40 arm, adapted to engage said first mentioned contact member, and guide means in connection with said support and said arm for retaining said contact members in alignment with each other.

45 3. In a heating apparatus, an electrical contact making and breaking means, including a support, a single freely movable plate, capable of being distorted by heat, loosely mounted on and encircled by said support, 50 a lever pivotally mounted at its one end on said support, adapted to be moved by said plate, a contact member mounted in said support, another contact member mounted at the opposite end of said lever in alignment 55 with said first mentioned contact member, resilient means in connection with said support and said lever for forcing said contact members into engagement with each other, and guide means in connection with said support and said lever for retaining said contact members in alignment with each other.

60 4. In a heating apparatus, an electrical contact making and breaking means, including a support, a single plate, capable of being 65 distorted by heat, mounted thereon and en-

circled thereby, a lever pivotally mounted at its one end, positioned contiguous to said plate, a contact member mounted on the opposite end of said lever, another contact member mounted contiguous thereto and in alignment therewith, an adjusting screw mounted in said lever, adapted to engage said plate, a resilient means in connection with said lever for forcing said contact members in engagement with each other, an adjusting lever mounted on said adjusting screw for adjusting the latter, and a clamp means in connection with said lever for frictionally connecting said lever to said adjusting screw.

5. In a heating apparatus, an electric contact making and breaking means, including a support, a thermostat plate mounted thereon, a movable contact supporting member positioned contiguous to said plate, a contact member mounted on said supporting member and insulated therefrom, a second contact member mounted in cooperative relationship with said first mentioned contact member, and a multi-thread adjusting screw mounted in said contact supporting member extending towards said plate and adapted to be engaged thereby, and an adjusting lever, movable over a restricted arc, adapted to rotate said adjusting screw for varying the space between said screw and plate, the limited movement of said lever effecting a full range of adjustment of said screw.

In testimony whereof, I have hereunto set my hand at San Diego, California, this 9th day of February, 1923.

MARTIN C. BERSTED.
